UNITED STATES PATENT OFFICE

130,736

DESIGN FOR A COMBINED DISPENSING AND DISPLAY CASE FOR PHONOGRAPH NEEDLES OR THE LIKE

Henry B. Babson, Chicago, Ill., assignor to
Pfanstiehl Chemical Company, a corporation
of Illinois

Application July 23, 1941, Serial No. 102,395

Term of patent 14 years

To all whom it may concern:

Be it known that I, Henry B. Babson, a citizen
of the United States, residing at Chicago, in the
county of Cook and State of Illinois, have in-
vented a new, original, and ornamental Design
for a Combined Dispensing and Display Case for
Phonograph Needles or the like, of which the fol-
lowing is a specification, reference being had to
the accompanying drawing forming a part there-
of, in which:

Figure 1 is a front elevational view of a com-

bined dispensing and display case for phonograph
needles or the like, showing my new design;

Figure 2 is a side elevational view; and

Figure 3 is a rear elevational view thereof.

The dominant feature of the design is shown
in full lines.

I claim:

The ornamental design for a combined dispens-
ing and display case for phonograph needles or
the like, as shown and described.

HENRY B. BABSON.
